Fig. 1

Fig. 2

A technical drawing of a rectangular frame. The top horizontal side is labeled '36' at each end. The left vertical side is labeled 'W' at the top and '36' at the bottom. The right vertical side is labeled '36' at the top and '16' at the bottom. The bottom horizontal side is labeled '13' at the top and '10' at the bottom. Inside the frame, there is a smaller rectangular opening. The top edge of this opening is labeled '9'. The left edge is labeled '8'. The right edge is labeled '21'. The bottom edge is labeled '1'. The entire frame is surrounded by a hatched pattern.

CABINET

Glenn E. Wise, 2415 39th Place NW., Washington, D.C.
Filed Dec. 8, 1960, Ser. No. 74,497
7 Claims. (Cl. 4-1)

This invention relates to a cabinet structure, and, more particularly, to a cabinet designed to cooperate with the flush tank of a conventional home-type toilet in such manner that the space above the tank may be utilized for storage without unduly hindering access to the flushing mechanism within the tank.

In the past, attempts have been made to design a cabinet to utilize the space above a toilet's flush tank for storage, but these previous attempts have suffered from one or more disadvantages. In some cases, the previous constructions prevented or greatly hindered access to the flushing mechanism within the flush tank in case of a malfunction. In other constructions, the cabinets were supported solely by the tank. This latter arrangement is undesirable because of the low structural strength of the materials of which flush tanks are normally constructed. Also, certain of the previous cabinets were designed for use with only one particular form of flush tank thereby rendering them useless for use with other forms.

Among the objects of this invention are to overcome the aforementioned disadvantages by providing a cabinet which is self-supporting, which has means designed to allow speedy access to the flushing mechanism within a toilet's flush tank, and which is designed so as to be useable with a great variety of toilets.

Other objects will be apparent from the remainder of the specification and from the drawings.

In the drawings which form a part of this specification:

FIGURE 1 is a front elevation of one form of my invention shown installed in its use position relative to a flush tank-including toilet;

FIGURE 2 is a right side elevation of the structure shown in FIGURE 1, with certain portions broken away to disclose internal structure;

FIGURE 3 is an enlarged sectional view taken on the line 3-3 of FIGURE 1, with portions broken away to disclose additional features.

FIGURE 4 is a sectional view taken on the line 4-4 of FIGURE 1;

FIGURE 5 is a sectional view taken on the line 5-5 of FIGURE 1;

FIGURE 6 is a partial front elevation showing a second form of the invention, with certain portions broken away to disclose internal structure;

FIGURE 7 is a right side elevation of the form of the invention shown in FIGURE 6, with certain parts broken away to disclose internal structure;

FIGURE 8 is an enlarged partial sectional view taken on the line 8-8 of FIGURE 6;

FIGURE 9 is an enlarged sectional view taken on the line 9-9 of FIGURE 6 showing how access into the flush tank is normally substantially blocked by a drawer employed in this form of the invention;

FIGURE 10 is an enlarged sectional view also taken on the line 9-9 of FIGURE 6, but with the aforementioned drawer removed so as to allow access into the flush tank; and,

FIGURE 11 is an enlarged partial elevational view of one of several identical extensible legs utilized in both forms of the invention.

Referring now to FIGURES 1 to 5 and 11 of the drawings by reference numerals, I show one form of my cabinet, designated generally by 1, positioned for use relative to a flush tank-including toilet, designated gen-

2

erally as 2. Toilet 2, as is conventional, consists of a bowl portion 3 having a seat 4 and cover 5 articulated thereto by means of a hinge structure 6. On the upper rear portion of the bowl portion 3 is positioned the usual flush tank 7, which includes a flush lever structure 8. The numeral 9 denotes the usual incoming water line.

For the sake of clarity, the flushing mechanism within the flush tank has been omitted from the drawings, but it is to be understood that in actual practice the conventional float, water outlet aperture, overflow pipe, etc. would be present.

F in the various views denotes a floor by which the toilet and cabinet are supported, and W denotes a wall perpendicular to the floor and adjacent the toilet and cabinet.

Cabinet 1, more particularly, includes a front wall 10, side walls 11 and 12, and a back wall 13. Elements 10, 11, 12 and 13 form a casing, and are preferably formed of sheet metal, but, alternatively, they may be made of wood or other suitable materials. The upper end of the cabinet is closed by a top 14, seen in FIGURE 2, which is spot-welded to the upper ends of each of elements 10, 11, 12 and 13. Since spot-welding is the conventional method of joining the various parts of sheet-metal cabinets of this type, I have not shown the individual weldments, but it is to be understood that in an actual construction such weldments would be present where necessary as dictated by structural requirements.

Each of elements 11, 12, 13 and 14 are plain rectangular sheet metal panels, but through front wall 10 is formed a large aperture 15, which allows access into the cabinet's interior, and a small aperture 16, which allows access into the flush tank, as will be seen.

Aperture 15 is normally covered by doors 17 and 18 which are mounted for swinging movement on wall 10 by means of conventional hinges 19. Each door is provided with a pull 20 as is conventional.

Aperture 16 is normally filled with a swingable panel 21. Panel 21 is pivotally mounted on wall 10 by means of a pair of conventional spring hinges 22 in such manner that said panel 21 is normally biased to close aperture 16, but so that said panel 21 can be swung inwardly as seen in phantom lines in FIGURE 3. By pushing inwardly on the bottom of panel 21, a person may insert his hand and arm through aperture 16 and thence into the interior of the flush tank should the flushing mechanism malfunction or require maintenance or adjustment. Details of the spring hinges 22 are not shown since any one of several conventional types would serve satisfactorily.

Panel 21 is prevented from swinging forwardly of a position where it is aligned with wall 10 because of an integral tongue 23 thereon (FIGURE 3) which engages with a stop ledge 24 which is integral with wall 10 and extends upwardly a short distance into aperture 16.

Spot welded to the lower inside portion of wall 11, and to portions of walls 10 and 13 adjacent thereto is a horizontally disposed leg-attachment plate 25 (FIGURES 3 and 4). An identical plate 26 is welded to the lower inside portion of wall 12 and to portions of walls 10 and 13 adjacent thereto.

Depending from the undersides of plates 25 and 26, and welded thereto, are four spaced leg-receiving sockets 27. Two sockets are fastened to each plate as best seen in FIGURE 4. Each socket carries internal threads 28, FIGURE 3, and in each socket is fixed the upper end of a leg tube 29 by means of exterior threads 30 (which mate with threads 28) formed thereon. Each leg tube 29 is provided with internal threads 31 at its lower end (see FIGURE 11).

Extending upwardly into each leg tube 29 is a stem 32 which carries at its lower end an integral foot member

33. Stem 32 is provided with external threads 34 which are adapted to mate with threads 31. Fastened to the underside of foot member 32 by means of glue is a circular pad 35 of rubber, or the like, for preventing damage to floor F.

In order to render the cabinet capable of sustaining the weight of articles stored therein, bracing is provided adjacent the inner sides of walls 10, 11, 12 and 13. In FIGURES 3, 4 and 5 are seen portions of four identical vertical angle iron braces 36 which are welded into the four vertically disposed corners formed where the aforementioned walls meet. Braces 36 extend, without interruption, from the tops of plates 25 and 26 to the underside of top 14.

Direct support for articles stored in cabinet 1 is provided by one or more shelves of the type seen at 37, FIGURES 2, 3 and 5. Shelf 37 is supported on, and may be welded to a plurality of horizontally disposed underlying brace members. In FIGURES 3 and 5, shelf 37 is seen supported on such brace members, namely, brace member 38, welded to the inside surface of wall 10, brace member 39, welded to the inside surface of wall 11, brace member 40, welded to the inside surface of wall 12, and brace members 41, welded to the inside surface of wall 13. The ends of each of brace members 38, 39, 40 and 41 are also welded to the ends of adjacent brace members.

The description of the various elements of the first form of my invention is now complete.

The installation and operation of cabinet 1 should be apparent from the drawings, but, for the sake of completeness, a description of such installation and operation follows:

To install cabinet 1, a person would first remove the usual cover (not shown) from the top of the flush tank 7 since it is no longer required. Next, cabinet 1 would be assembled adjacent toilet 2, and, when assembled, its legs would be extended evenly until the bottom edges of walls 10 and 13 were slightly higher than the top edge of tank 7. Cabinet 1 would then be maneuvered so as to overlie flush tank 7, and, after it was properly centered over the tank, the legs would be shortened until the top edge of tank 7 extended upwardly a small distance into the space defined within the walls 10, 11, 12 and 13 as seen in FIGURES 1, 2 and 3. Care must be taken at this time to insure that the top of tank 7 does not extend into cabinet 1 so far as to prevent panel 21 from swinging inwardly, as previously described. By additional manipulations, cabinet 1 is now oriented so that the rear surface of the lower end of wall 10 is flush with the front surface of the front wall of tank 7. When cabinet 1 is so oriented, the rear surface of rear wall 13 will be substantially flush with the front surface of room wall W if toilet 2 is positioned relative to W as seen in FIGURES 2 to 5. If the toilet is located farther from wall W, then there will be a space between wall 13 and wall W as seen in the embodiment shown in FIGURES 6 to 10. At this juncture the cabinet 1 is adjusted to level position by manipulating stems 32 relative to tubes 29.

It should be noted that the storage portion of cabinet 1 can be produced in various dimensions. Obviously, however, an overlying room ceiling would serve as a maximum limit to the height of cabinet 1.

Once cabinet 1 is installed, as described, the doors may be opened and various articles, for example, soap, towels, tissues, may be placed on one or more shelves of the type denoted 37. It will be apparent that such storage would be extremely convenient. After articles are placed in the cabinet, doors 17 and 18 are swung closed against wall 10. Magnetic, or other conventional closure fasteners (not shown) may be employed to retain the doors in closed position.

Should a malfunction occur in the flushing mechanism within flush tank 7 after cabinet 1 is installed thereover, a person can gain access to the interior of tank 7, and

thus the flushing mechanism, merely by pushing inwardly on the bottom of panel 21. Such inward pressure causes panel 21 to swing inwardly and upwardly against the bias of the hinges 22, thus opening aperture 16. After the malfunction is repaired, pressure against panel 21 is released and it again swings flush with wall 10 due to the bias of spring hinges 22.

A second embodiment of the invention is seen in FIGURES 6 to 10. This second embodiment differs from the first embodiment only in the means employed for allowing access to the interior of a toilet's flush tank once the cabinet has been installed thereover and, therefore, only so much of the cabinet and toilet structure necessary to illustrate this modification is shown in FIGURES 6 to 10. The portions of the cabinet and toilet not shown in FIGURES 6 to 10 are identical to those illustrated in FIGURES 1 to 5 and 11, for example, the cabinet's extensible legs.

Referring now to FIGURES 6 to 10 by reference numerals, the second form of my cabinet, designated generally as 101, is shown positioned for use relative to the flush tank 107 of a conventional toilet. The numeral 108 denotes a conventional flushing lever mounted on the tank. Again the remainder of the flushing mechanism normally located within such a flush tank has been omitted for the sake of clarity. W again denotes a wall adjacent which the toilet and cabinet are located.

Cabinet 101, more particularly, includes a front wall 110, side walls 111 and 112, and a back wall 113. The upper end of cabinet 101 is closed by a top 114, seen in FIGURE 7, which is welded to the upper end of each of walls 110, 111, 112 and 113. As in the case of the first form of cabinet designated 1, I prefer to fabricate cabinet 101 from sheet metal with spot welding employed where required to unite the various parts together.

Each of elements 110, 111, 112 and 113 are plane rectangular panels, but front wall differs since it has formed therethrough a large aperture 115, which allows access into the interior of cabinet 101, and a small aperture 116, as will be seen, allows access into the interior of flush tank 107.

Aperture 115 is normally covered by doors 117 and 118 which are mounted for swinging movement on wall 110 by means of conventional hinges 119. Each door is provided with a pull 120 as is conventional.

Aperture 116 is normally filled with the front board 121 of a drawer designated generally at D, to be fully described hereinafter.

Spot welded to the lower inside portion of wall 111, and to portions of walls 110 and 113 adjacent thereto is a horizontally disposed leg-attachment plate 125. An identical plate 126 is welded to the lower inside portion of wall 112 and to portions of walls 110 and 113 adjacent thereto.

Depending from the undersides of plates 125 and 126, and welded thereto, are four leg-receiving sockets 27 which are identical to the sockets 27 on cabinet 1. The remainder of the extensible leg-forming elements of cabinet 101 are also identical to those of cabinet 1 and, therefore, further description of these elements is deemed unnecessary.

Drawer D, previously mentioned, in addition to front board 121, includes two sides 127 and 128, a back board 129 and a bottom 130 which elements are welded together in conventional fashion. Drawer D is supported for linear movement into and out of a position where it overlies tank 107 (see FIGURE 8) on spaced parallel angle iron guide rails 131 and 132. These rails are horizontally disposed and their respective ends abut and are welded to walls 110 and 113. To aid a user in opening drawer D, finger-receiving aperture 133 is formed in front board 121. Drawer D is shown closed in full lines, and partially opened in phantom lines in FIGURE 8. By pulling straight forwardly on the drawer it can

be removed entirely from the remainder of cabinet 101 when desired.

Vertical angle iron braces identical to braces 36 in cabinet 1 are employed in like manner in cabinet 101 where they are denoted by 136.

Direct support for articles stored in cabinet 101 is provided by one or more shelves of the type seen at 137, FIGURES 7 and 8. Shelf 137 is supported on, and may be welded to a plurality of horizontally disposed underlying brace members. In FIGURE 8, shelf 137 is seen supported on such brace members, namely: brace member 138, welded to the inside surface of wall 110; brace member 139, welded to the inside surface of wall 111; and brace member 141, welded to the inside surface of wall 113. A further brace member, not shown, identical with brace member 40, FIGURE 5, can also be welded to the inside surface of wall 112 to complete the shelf supporting structure. The ends of each of brace members 138, 139 and 141 may be welded to the ends of adjacent brace members.

The description of the various elements of the second form of the invention is now complete.

Installation of cabinet 101 relative to flush tank 107 would be accomplished in the same manner in which cabinet 1 was installed relative to tank 7. However, in FIGURES 7 to 10, I depict a situation wherein the tank-including toilet has been installed an appreciable distance from wall W, thus leaving an open space between wall W and wall 113 of cabinet 101 when cabinet 101 is in its use location.

It should here be noted that either of cabinets 1 or 101 are also usable with toilet installations wherein a toilet's flush tank is either in engagement with or hung from a lower portion of wall W. To use either form of cabinet with such a toilet installation it is only necessary that the central portion of the lower edge of wall 13 or wall 113 be cut away enough to allow such a flush tank to protrude up into the open space defined by either cabinet's front and side walls a distance equal to that shown in FIGURES 3 or 8.

As noted in regard to cabinet 1, the storage portion of cabinet 101 can be produced in various dimensions. Obviously, however, an overlying room ceiling would serve as a maximum limit to the height of cabinet 101.

Once cabinet 101 is installed, the doors may be opened and various articles may be placed on shelf 137 (and on other similar shelves if they are employed). After articles are placed in the cabinet, doors 117 and 118 are swung closed against wall 110 thus covering aperture 115. Again, as mentioned regarding cabinet 1, magnetic or other conventional closure fasteners (not shown) may be employed to retain the doors in closed position.

Should a malfunction occur in the flushing mechanism within flush tank 107 after cabinet 101 is installed thereover, a person may gain access to the interior of tank 107 and, thus, the flushing mechanism, merely by removing drawer D. With drawer D removed from cabinet 101, a person may then insert an arm or arms through aperture 116 and thence down into tank 107. After the malfunction is repaired, drawer D is reinserted into aperture 116 and pushed rearwardly until the back board 129 thereof abuts rear wall 113 at which time the drawer's front board 121 will be flush with front wall 110 thereby completely filling aperture 116.

If it is deemed desirable to achieve the tank access provided by either form of cabinet shown in the drawings without the expense of providing for panel 21 or drawer D, then the panel or drawer can be omitted, and the respective cabinets' doors may be extended downwardly to normally cover the tank access apertures 16 and 116. More specifically, in FIGURE 1, panel 21 and spring hinges 22 may be deleted and doors 17 and 18 extended downwardly to normally cover aperture 16, and in FIGURE 6, drawer D and guide rails 131 and 132 may be

deleted and doors 117 and 118 may be extended to normally cover aperture 116. Obviously, when access to the flushing mechanism in either of tanks 7 or 107 is desired, it is only necessary to open doors 17 and 18, or 117 and 118, respectively, to expose apertures 16 or 116, respectively.

The necessity for providing panel 21 or drawer D or apertures 16 or 116 for access into the flush tank can be negated by the simple expedient of not fastening shelves 37 or 137 to their respective supports. With such constructions, access to the respective tanks 7 or 107 may be gained merely by opening doors 17 and 18 or 117 and 118, respectively, and removing shelf 37 or 137, as the case may be.

It is obvious that many modifications might be made in the various embodiments of this invention without departing from the spirit thereof. For example, other types of extensible legs might be utilized, and other equivalent forms of cabinet and drawer constructions might be employed.

Having set forth my invention, what I claim and desire to secure by Letters Patent is:

1. In combination: a floor portion; a toilet including a bowl portion and a flush tank having a hollow interior; means supporting said toilet; a unitary portable cabinet structure supported by said floor portion and adapted for engagement with but structurally detached from and, thus, movable as a unit relative to said toilet, said cabinet including wall-forming means, entry means supported by said wall-forming means for movement relative to said wall-forming means, and means, engaging said floor portion and said wall-forming means supporting said wall-forming means, said wall-forming means and said entry means normally cooperating with portions of said tank to prevent direct entry of a hand into said interior, said entry means being movable, however, as aforesaid, to allow direct entry of a hand into said interior when such entry is desired.

2. In combination: a floor portion; a toilet including a bowl portion and a flush tank having a hollow interior; means supporting said toilet; a unitary portable cabinet structure supported by said floor portion and adapted for engagement with but structurally detached from and, thus, movable relative to said toilet, said cabinet including wall-forming means and entry means attached to said wall-forming means, said entry means being movable relative to said wall-forming means whereby said entry means can either be positioned to cooperate with said tank and said wall-forming means in such manner as to prevent entry of a hand into said interior, or positioned relative to said tank and said wall-forming means so as to allow entry of a hand into said interior.

3. The combination of claim 1, said means supported by said wall-forming means comprising an element upon which articles may be placed for storage.

4. The combination of claim 3, said element forming the bottom board of a drawer.

5. The combination of claim 1, said means supported by said wall-forming means comprising at least one pivoted panel.

6. The combination of claim 1, said means supporting said wall-forming means comprising a plurality of legs the lower ends of which engage said floor portion.

7. The combination of claim 6, said legs including means for adjusting the length thereof.
